UNITED STATES PATENT OFFICE

CLARENCE J. BLEIL, OF LOS ANGELES, CALIFORNIA

MIXING APPARATUS

Application filed January 29, 1927. Serial No. 164,520.

This invention is an apparatus for use in extracting oils and oleaginous constituents from seeds, sewage, and other masses of oil containing material.

5 One of the objects of the invention is to provide an apparatus for mixing solvent and the oil carrying material to be treated, as a preliminary step to delivering the mixture to a suitable filtering apparatus.

10 The invention will be hereinafter set forth and particularly pointed out in the claims.

In the accompanying drawing:—

The figure is a longitudinal sectional view illustrating the incorporator.

15 Referring to the drawing, the mixer A consists of a cylindrical casing and may be supported either horizontally or in a tilted position, but preferably slightly inclined downwardly toward the discharge end. It is

20 divided into a plurality of compartments by baffle plates 70 which are staggered so as to insure that material moving through the casing shall be caused to travel a tortuous path. Material is fed through a feed opening 71 at

25 the top, said opening being closed by valves 72 and 73 so arranged that they may be alternately opened and closed and thereby provide for feeding the material to the incorporator without substantial loss of vacuum.

30 Located within the compartments produced by the partitions 70 are paddles 74, mounted on a shaft 75 extending through the incorporator and driven by suitable power means, a drive wheel 76 being illustrated for this purpose.

35 The incorporator is provided with an end compartment having an outlet 77 which delivers the material to the pipe 11.

If for any reason discharge of the material through the outlet 77 should become temporarily arrested, it is important to empty 40 the incorporator, so as to prevent the solidifying of the material therein to such an extent as to make it impossible to rotate the shaft 75. To facilitate emptying of the incorporator under such conditions, a valve 78

45 is provided in one of the partitions 70 so that a passageway may be opened along the bottom part of the incorporator, and the material may then be delivered through the 50 pipe 79 to an emergency tank (not shown),

and from thence forced by the pump 81 and pipe 82 to the filter, when desired. In this way the contents of the incorporator may be emptied into the emergency tank and held until required. The emergency tank also 55 communicates with the solvent tanks through the medium of the pipe 83^a and pump D, as shown, so that solvent may be forced into the emergency tank to make its contents sufficiently fluid to insure its ready flow out 60 through the pipe 82. During the normal operation of the mixer the flow of material through the pipe 29 is prevented by means of a suitable valve.

In practice, it is preferred to finely divide, 65 in suitable manner, any desirable oil bearing material and to mix it with any desired quantity of solvent. The mixing of the material and the solvent is effected by introducing them into the mixer at practically the same 70 time, the solvent being intimately mixed with the oil-bearing material by reason of the agitation of the paddles 74, during the passage of the ingredients through the incorporator A.

Having thus explained the nature of the invention and described an operative manner of constructing and using the same, although without attempting to set forth all of the forms in which it may be made, or all 75 of the forms of its use, what is claimed is:—

1. In an apparatus for extracting oleaginous constituents, a mixer comprising a closed chamber provided with staggered baffle plates, means for feeding the oil bearing material into said chamber, means for introducing a solvent into said chamber, and means for intimately mixing the solvent and the material and forcing said mixing means being constructed to force said mixed materials to travel through said mixer.

2. In an apparatus for extracting oleaginous constituents, a mixing chamber provided with staggered baffle plates dividing the same into a plurality of communicating 95 compartments, a shaft extending through all of said compartments and provided with agitators located in the respective compartments, means for rotating said shaft, and means for introducing the oil bearing material and a 100

solvent into said mixing chamber, said agitators being shaped to force said material to travel longitudinally of said chamber and around the baffle plates.

5 3. In an apparatus for extracting oleaginous constituents, a mixing chamber provided with staggered baffle plates forming a plurality of communicating chambers, a valve in one of said baffle plates, agitators in the respective chambers for causing the material to travel in a tortuous path through the chamber, means for introducing the oil bearing material and a solvent in said mixing chamber, and means for operating said valve so that the material will travel in a straight line instead of in a tortuous path.

10 4. In an apparatus for extracting oleaginous constituents, a mixing chamber provided with an inlet and an outlet, means within said chamber for causing the mixture to travel in a tortuous path, and means by which the mixture may be caused to travel in a straight path to said outlet.

15 In testimony whereof I have hereunto set
20 my hand.

25 CLARENCE J. BLEIL.
